CONTROL MECHANISM FOR SCREW MACHINES

Xavier François Castelli, Paris, France, assignor to society called Societe Cri-Dan, Paris, France

Application January 8, 1946, Serial No. 639,774
In France January 10, 1945

3 Claims. (Cl. 10—101)

1

The present invention relates to screw-cutting machines of the kind which performs a succession of operations similar to that of a semi-automatic lathe, i. e.: first cut, retraction of the tool, quick return, depth stroke for the next cut, second cut, and so on, until the work is performed but in which the longitudinal displacement of the toolholder is controlled by a rotating cam which is rotated from the driving spindle for the piece to be threaded while the progressive transverse advance of the tool, after each cut, is controlled by another cam intermittently rotated, also from the spindle, through a ratchet-wheel and a ratchet-mechanism, the various mechanisms being automatically stopped when the number of cuts selected to perform the thread has been reached.

Attempts have been heretofore made to perform, with machines of that kind, screw-cutting with multiple threads, but the apparatus proposed to that end, being generally of an irrational conception, were not adapted, in the majority of the works they were intended to perform, to effect a uniform spacing of the cuts between the different threads and to achieve strictly identical depths of each of the latter.

The invention has for its object to produce a machine for cutting multiple threads in a remarkably simple manner, whatever may be the number of threads to be formed.

The process according to the invention substantially consists in angularly moving the cam which controls the transverse advance of the tool, in order to secure the drive of the tool to the depth corresponding to the cut to be made, only once before each series of cuts corresponding to the number of threads to be formed, and to maintain said cam stationary while the tool is performing said series of cuts, and correlatively realizing, between the driving spindle for the piece to be threaded and the cam controlling the longitudinal displacements of the tool, a speed ratio such that the complete revolution of the last cam corresponds to an integer number of complete turns of the spindle plus a fraction of a turn of said spindle equal to the inverse of the number of threads to be cut.

In other words, if a threading of n threads is to be effected, the cam for the transverse advance is angularly displaced, to give the advance depth for each successive cut, only once before each series of n cuts and is maintained stationary during the time said n cuts are performed, while the speed ratio between the spindle and the cam for the longitudinal displacements (pitch cam) is

2

selected such that the complete revolution of said pitch cam corresponds to an integer number of complete turns of the spindle plus a fraction equal to $1/n$ of a turn of said spindle.

In such conditions, the threading tool, after each cut, is effectively longitudinally displaced with respect to the previous thread cut; this displacement is equal to $1/n$ times the lead given by the pitch cam, i. e. to the width of one of the n threads to be formed; the tool returns to its normal starting position, corresponding to the beginning of the first thread, when n cuts have been performed. The cam for the transverse advance remaining stationary during said n cuts, the tool is maintained at the same depth, so that said cuts are successively performed on each of said n threads, at the rate of one cut for one thread, exactly at the same depth, a new advance of the tool being only realized for a successive series of n cuts, when the previous series of n cuts have been performed.

I have shown in the appended drawing an embodiment of the invention as applied to a control mechanism for the transverse advance of the tool in a screw-cutting machine of the type described in my copending patent application Serial No. 639,773, filed January 8, 1946, now Patent No. 2,576,570, granted November 27, 1951, for "Screw Machine," but it is to be understood that such a mechanism is adapted to be combined with any screw machine which comprises a control for the advance cam by means of a ratchet-wheel.

Other characteristics of this invention will appear from the following description of an embodiment thereof taken in connection with the annexed drawings in which:

Fig. 1 is an elevation view of the control mechanism of the cam for the transverse advance;

Fig. 2 is a partial section through II—II of Fig. 1 looking upwardly from the section line;

Fig. 3 is a partial view of the mechanism shown in Fig. 1, in another position for working;

Figs. 4 and 5 are views of the same mechanism in two other positions of working;

Figs. 6 to 8 show different rotating members corresponding to the execution of different numbers of threads.

Figure 9 is a perspective view of the operating parts of a screw machine of the type described in my co-pending patent application, the frame, casings and supports being omitted.

Figure 9A is a perspective view on a larger scale of that portion appearing on the left-hand part of Figure 9.

55 First, the exact location of the device according

to the present invention in the entire machine will be positioned according to Figure 9, and the part played by each member connected mechanically to this device will be briefly described. In the example shown in Figure 9, the machine comprises a work bed 101 on which are mounted, on the one hand, a driving spindle 102 for the work piece and, on the other hand, a carrier 103, stationary during working but the longitudinal position of which may be varied. The rotation of the spindle 102 is controlled by means of a pulley 104 coaxial of the spindle and connected by belts 105 with a motor (not shown). The carrier 103 supports a longitudinal carriage 106, which is mounted so as to freely slide on the carrier. On the longitudinal carriage 106 is mounted a transversely movable carriage 107 on which is mounted in a selected position a second transversely movable carriage 108 carrying a tool-holder turret 109. Moreover, the carrier 103 supports, on the side opposite the apron of the machine, the mechanisms adapted to automatically control the movement of the carriages 106 and 107. These mechanisms, which are arranged at the front of Figure 9, shall be further described hereinafter.

At its rear end, the spindle 102 carries a pinion 110, through which it transmits its rotation to the mechanisms of the carrier. To this end, the pinion 110 meshes with a toothed wheel 111 keyed to a shaft 112. The shaft 112 carries a pinion 113, which drives a removable set of gears 114, 115 and 116, the shafts 117 and 118 of which are mounted on a support 119 adapted to be locked in the correct meshing position by means of bolts 120. These gears, together with the pinion 113 which is also removable, determine the step down ratio between the speed of rotation of the spindle 102 and the speed of the mechanisms carried by the carrier 103. The shaft 118 of the last gear 116 carries a pinion 121 adapted to mesh, at will, with one or the other of two pinions 122 and 123 mounted on a movable support 124 acting as motion-reversing means in order to produce left or right handed threads. The pinion 121 is maintained in the desired position of rotation by means of locking bolts 125. The two inverting pinions 122 and 123 cooperate with a last pinion 126 keyed to a longitudinal shaft 127, which terminates inside the carrier 103 where it carries a pinion 128 which is fixed to it for rotation by a key 129. The key 129 enters a longitudinal groove 127a cut in the shaft 127, in which it can freely slide, thereby enabling the pinion 128 to be moved along the shaft 127 together with the carrier 103 when the longitudinal position of the latter is adjusted. The pinion 128 meshes with a toothed wheel 130 keyed to a shaft 131, which carries at its end near the toothed wheel 130 a cam 132. The cam 132 engages a roller 133 fixed under the corresponding end of the longitudinal carriage 106. The roller 133 is urged into engagement with the cam 132 by two springs 134 disposed under the carriage 106, thereby urging the carriage in a direction away from the spindle 102. The cam 132, which is referred to as "pitch cam," controls the longitudinal movements of the carriage 106 and consequently of the tool (not shown) carried by the tool holder 109. The cam 132 determines the maximum length and the pitch of the screw to be cut, account being taken of the rotational speed given by the set of gears interposed between the spindle 102 and the shaft 127.

On the end of the shaft 131 opposed to that carrying the cam 126 are mounted two coupled cams 135 and 136 encased one in the other, and

acting on a roller 137 carried by a lever 138, the lower end of which is mounted on a fixed pin 139. A compressed spring 140 acts on the lever 138 to permanently maintain the roller 137 in contact with the cams 135 and 136. At its upper end, the lever 138 is connected by means of a cardan joint 141 to a bar 142, which operates in a longitudinal slide (not shown) provided in the carrier 103. The free end of the bar 142 is fitted with a slope 142a, which terminates in a part 142b of less thickness, such part contacting one of the arms of a rocking lever 143 pivotally mounted on the carrier 103 by means of an axle 144. The other arm of the lever 143 bears on a pushing rod 145, which is in contact with a control element 146 fixed on the transverse carriage 107, said pushing rod transmitting to the carriage 107, and thus to the tool, the transverse feeding motions against the action of a compressed spring 147 interposed between the longitudinal carriage 106 and the transverse carriage 107 and which tends to drive the latter toward the operator. The transverse feeding motions are controlled by a double eccentric cam 148 mounted on a rotatable shaft 148a and which acts on a pushing rod 149 connected by a ball and socket joint to a sliding bushing 150. The sliding bushing is adjustable in height and is fixed on one arm of a pivotally mounted lever 151, the other arm of which contacts the bar 142 in front of the rocking lever 143. Thus, the cam 148, which is referred to as "the feeding cam," controls through the parts 149, 150, 151, 142, 143, 145, 146 and the carriage 107, the progressive advance in depth of the tool.

The rotation of the feeding cam 148 is controlled by the mechanism hereinafter described (see also Figures 1 and 2). This mechanism comprises a ratchet-wheel 1 keyed to a shaft 2 carrying a pinion 152, which meshes with a curved rack 153 fixed on the shaft 148a. The rotation of the ratchet wheel 1 is controlled by means of a driving pawl 3 pivotally mounted through an axle 4 on a lever 5, which itself is pivotally mounted on a stationary axle 6; the lever 5 receives, after each cut, a rocking movement upon the axle 6, in the direction of the arrow f1, through the action of a connecting rod 7 connected to the lever 138. The amplitude of said movement is such that the angular movement transmitted each time by the pawl 3 to the ratchet-wheel 1 corresponds to one tooth of the latter. The reverse rotation of the ratchet-wheel is prevented by a stop-pawl 8. The two pawls 3 and 8 are normally maintained in engagement with said wheel through springs 9 and 10.

To allow determining, according to the conditions of the threading, the number of cuts in which the total advance of the tool is to be effected, one face of the ratchet-wheel 1 (Fig. 2) is made fast to a plate 11 carrying a lug or pin 12 which can be engaged, at will, in one of the holes 13a provided on the same circumference in a coaxial idle plate 13 mounted on the shaft 2, each of said holes corresponding to a determined number of cuts. The plate 13 carries a finger 14, on the trajectory of which is disposed a lever 15 keyed on a shaft 16 mounted in parallel relation to the shaft 2 of the ratchet-wheel. On the shaft 16 is keyed a second lever 17 with two arms, whose lower arm 17a is located opposite a lug 18 provided on the stopping pawl 8. The lever 17 in turn drives, through a convenient key connection, a third lever 19 mounted on the shaft 16, whose lower arm 19a is located opposite a lug 20 provided on the driving-pawl 3. The disposition of said

members is such that, when the finger 14 of the plate 13 bears upon the lever 15, i. e. when the selected number of cuts is achieved, the levers 17 and 19 bear respectively, through their lower arms 17a and 19a, upon the lugs 18 and 20 of the pawls 8 and 3, raise said two ratchets and clear the ratchet-wheel 1 and the plate 13. The feeding cam 148 is then returned to its first position through a spring 154 connected to the shaft 148a. Simultaneously, the rotation of the shaft 16 determines, through the medium of the following mechanism, the freeing and the braking of the driving spindle for the piece to be threaded, and, consequently, the automatic stopping of the machine. To this end, the shaft 16 carries an helicoidal pinion 155 (see Figure 9), meshing with a pinion 156 keyed to a shaft 157, which terminates near the spindle 102. At its end located near the spindle, the shaft 157 carries a lever 158 urged by a spring 159 and which controls through a bolt 160 a lever 161 urged by a spring 162. When the shaft 16 is angularly moved by the thrust of the finger 14 of the perforated plate 13 acting on the lever 15, the shaft 157 is itself rotated through the pinions 155 and 156 and provides through the lever 158 for the lowering of the bolt 160, thereby clearing the lever 161. The lever 161 actuates the clutch cone 163 away from the cone 164 of the pulley 104 and engages the braking cone 165 with the stationary cone 166, thus automatically stopping the rotation of the spindle 102 and, consequently, the working of the whole of the mechanisms carried by the carrier 103.

Above the shaft 16 is disposed another shaft 21 carrying, at one of its free ends, a controlling lever 22. On said shaft is keyed a lever comprising two arms 23—24 lying in different planes. The arm 23 is located opposite the upper arm 19b of the lever 19, so that, when the controlling lever 22 is rotated in the direction of the arrow f_2 (Fig. 4), said arm 23 rocks the lever 19 which, acting upon the lug 20 of the driving pawl 3, disconnects the latter from the ratchet-wheel 1; the rotation of said wheel is thus prevented and the machine runs idle, the tool remaining at the same cutting-depth, which allows completing the adjustment of the tool or testing the operations after each cut. The arm 24 is disposed opposite a double lever 25 which, when the controlling lever 22 is rotated in the direction of the arrow f_3 (Fig. 5) acts upon the upper hand 17b of the lever 17, with the result, through the intermediary of the latter and of the lever 19, of disengaging of the pawls 8 and 3, and, thus, of stopping the machine in conditions similar to that accompanying the automatic disengagement at the end of the work.

According to the present invention, in order to allow performing multiple threads by means of a mechanism of the kind above described, an interchangeable rotating member or disc 26 is mounted on the face of the rocking lever 5 carrying the driving pawl 3, near the tail of the latter. Said rotating member is keyed on an axle 27 which is free to rotate in the lever 5, but on which is fixed a ratchet-wheel 28 with which are in engagement, on the one hand, a driving pawl 29 mounted on a fixed axle 30 disposed outside the lever 5 and, on the other hand, a movable stopping pawl 31 carried by the lever 5. The arrangement is such that, when the lever 5 rocks in a direction opposed to that of the arrow f_1 , at each new cut, the fixed pawl 29 induces an angular movement, in the direction of the arrow f_4 of the ratchet-wheel 28 and, consequently, of the rotating member 26, movement which corresponds to

a tooth of said wheel, while the ratchet 31 holds the rotating member from retrograde movement. In the example shown in Figs. 1, 3, 4 and 5, which corresponds to the operation of a threading with four threads, the ratchet wheel 28 is fitted with twelve teeth and the rotating member 26 is of a circular outline on which are provided, at 120° one from the other, three notches 26a whose amplitude is equal to that of a tooth of the ratchet-wheel 28, each of the plain circular parts 26b corresponding thus to three teeth of the same ratchet-wheel. The rotating member 26 is disposed, with respect to the tail of the pawl 3, so that, when the parts 26b contact the tail of said pawl as in Figure 1, they push back the latter against its spring 9 and clear the same from the ratchet-wheel 1 which controls the cam 148 for the transverse advance of the tool, while, when the notches 26a are opposite the tail of the pawl 3, as in Figure 3, the latter remains in engagement with the ratchet-wheel 1.

The operation of the mechanism so constructed clearly results from the preceding explanation.

For example, to accomplish a threading comprising four threads, as contemplated above, the gears connecting the driving spindle 182 for the work piece with the shaft 127 controlling the pitch-cam 132 are chosen so that the complete revolution of said cam corresponds to an integral number of complete turns of the spindle plus a quarter of a turn of the spindle. Under such conditions the transverse position of the cutting tool remains the same for four threading passes; i. e. there is no change in depth of cut after each of the first, second and third threading passes. However, after each of the first, second, and third threading passes, the tool is longitudinally displaced relative to the work piece and the thread just previously cut by an amount equal to one-fourth the lead given by the pitch cam 132. After the fourth thread is cut, a similar longitudinal displacement of the tool relative to the work effectively returns the tool to its normal starting position corresponding to the position of the first thread.

During the first cut on the first thread, the rotating member 26 is in the position shown in Fig. 1, one of notches 26a being opposite the tail of the pawl 3, and the latter remaining thus in engagement with the ratchet-wheel. At the end of said cut, the rocking of the lever 5 in the direction of the arrow f_1 determines a rotation of the rotating member 26 in the direction of the arrow f_4 , having the value of one tooth of the ratchet-wheel 28, and the plain part 26b, adjacent to the aforesaid notch 26a, pushes back the pawl 3 and disengages it from the ratchet-wheel 1. The latter, and consequently the cam 148 controlling the transverse advance of the tool, remains thus stationary for the next cut and the tool remains at the same depth, so that said cut is performed on the second thread exactly at the same depth as on the first. It is identically operated for each of the two next cuts related to the third and fourth threads. At the end of the fourth cut, the rotating member 26 is brought in a position where the next notch 26a is in turn opposite the tail of the pawl 3, and the latter determines, through the rocking of the lever 5, a rotation of the ratchet-wheel 1 of one tooth, from which it results, by means of the cam 148 connected to said wheel, a transverse advance of the tool for the next four cuts.

The same operation is reproduced until the desired number of cuts has been performed on

each of the four threads. At this time, the finger 14 of the plate 13 raises the lever 15, and, by means of the levers 17—19, successively disengages the pawls 8 and 3 and stops the mechanism through the above described process.

As it can be understood, it is possible to accomplish, in similar conditions, threadings which comprise any number of threads by substituting appropriate rotating members for the member 26 and by selecting appropriate gear ratio between the driving spindle 102 and the shaft 131 of the pitch-cam 132. E. g., to accomplish a threading composed of six threads—the ratchet-wheel 28 having twelve teeth as above—one can use a rotating member such as the one shown in Fig. 6, which comprises two notches 26a having an amplitude equal to that of one tooth of the ratchet-wheel 28 and two plain circular parts 26b, each corresponding to five teeth of said wheel, and realize, between the pitch cam and the spindle, a speed ratio such that the rotation of the cam corresponds to a number of complete revolutions of the spindle plus $1/6$ of a turn of said spindle. Fig. 7 shows a rotating member adapted to accomplish a threading comprising three threads; said member comprises four notches 26a corresponding to one tooth of the ratchet-wheel 28 and four plain circular parts 26b respectively corresponding to two teeth of said wheel. Fig. 8 shows a rotating member for a threading comprising two threads, with six notches 26a and six plain parts 26b each corresponding to one tooth of the ratchet-wheel 28.

What I claim is:

1. A device for forming multiple screw threads by using a screw machine of the type in which the longitudinal movement of the tool-holder is controlled by a rotative cam which is actuated by the driving spindle of the machine while the progressive transverse advance of the tool, after each cut, is controlled by another cam intermittently actuated by the same spindle, through the intermediary of a ratchet-wheel driven by a pawl, said device comprising, in combination, a removable and interchangeable rotating part mounted near the driving pawl of the ratchet-wheel which controls the cam for the transverse advance, means for intermittently actuating said part in synchronism with said driving ratchet, and means to establish, between the speed of the driving spindle for the work piece and the speed of the cam which controls the longitudinal movements of the tool, such a ratio that the rotation of said last cam corresponds to an integer number of complete revolutions of the spindle plus a fraction of the last turn equal to the inverse of the number of threads to be cut, said rotating part being given such an outline that, for a portion of an amplitude corresponding to an angular movement of one tooth of the ratchet-wheel, said part is without action on the driving pawl of said wheel which is left in engagement with the latter, whilst on the next portion, whose amplitude is equal to as many times that of the preceding portion as the threading comprises threads minus one, it maintains the pawl out of engagement with said ratchet-wheel.

2. A screw machine comprising a frame, a driving spindle rotatively mounted on said frame for the work piece, a tool-holder mounted on said

frame, a controlling mechanism actuated by said driving spindle for imparting to said tool-holder to and fro movement parallel to the axis of said spindle, and means including a rotative cam intermittently actuated by said spindle through the intermediary of a ratchet wheel for imparting to said tool-holder in timed relation to said to and fro movement a progressive advancing movement at right angle to the axis of said spindle, said advancing means comprising a lever mounted on said frame for rocking movement, a driving pawl mounted on a face of said lever to actuate said ratchet-wheel, means in relation with said controlling mechanism for imparting to said lever a rocking movement in timed relation to said to and fro movement, a removable and interchangeable rotating part mounted on the face of said lever carrying said driving pawl, a fixed axle disposed on said frame outside said lever, a second pawl mounted on said axle, and a second ratchet wheel made fast coaxially to said rotating part and engaging, at each rocking movement of said lever, with said second pawl to induce an angular movement of said part, corresponding to a tooth of said second ratchet wheel, said rotating part being given such an outline that, for a portion of said outline of an amplitude corresponding to an angular movement of one tooth of said first ratchet wheel, said part is without action on the first driving pawl which is left in engagement with said first ratchet-wheel, whilst on the next portion, whose amplitude is equal to as many times of the preceding portion as the threading comprises threads minus one, it maintains said first pawl out of engagement with said first ratchet-wheel.

3. A device according to claim 2, in which said rotating part comprises a circular member having at the periphery thereof regularly spaced notches, full circular parts between said notches, the amplitude of each notch corresponding to an angular movement of one tooth of said second ratchet-wheel, the amplitude of each of said full circular parts corresponding to an angular movement of said second ratchet-wheel of as many teeth as the threading has threads minus one, and said circular member being so disposed with respect to said first driving pawl that when one of said notches is facing said first driving pawl, the latter is maintained in engagement with said first ratchet wheel, but when one of said full circular parts is facing said first driving pawl, the latter is maintained out of engagement with said first ratchet wheel.
